UNITED STATES PATENT OFFICE

WILLIAM M. HEINA, OF LONG ISLAND CITY, NEW YORK, ASSIGNOR TO AUTOMOBILE
RADIO CORPORATION, A CORPORATION OF DELAWARE

ELECTRICAL RESISTANCE UNIT AND TERMINAL

Application filed January 15, 1929. Serial No. 332,621.

This invention relates to an electrical resistance unit and terminal for attachment to the end of an electric wire conductor.

Among the objects of this invention is the provision of a rugged, compact and neat device of the character described which shall comprise few and simple parts, permitting ease of assembly and handling, which shall be comparatively inexpensive to manufacture and shall yet be practical and efficient to a high degree.

Other objects of this invention, will in part be obvious and in part hereinafter pointed out.

15 The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

25 Fig. 1 is a longitudinal partial cross-sectional view of a device embodying the invention attached to a piece of insulated wire, showing the parts only partially assembled,

30 Fig. 2 is a longitudinal view of the assembled device with parts broken away to disclose the interior construction.

Referring in detail to the drawing, 10 designates a portion of an ordinary flexible lead or conductor, here seen to comprise a stranded wire 11 covered by the usual insulating coating 12. Attached to one end of said conductor 10, in a manner hereinafter appearing, is a high resistance unit 14 adapted for various uses such as, for example, attaining a 40 high damping co-efficient for an electric circuit.

Said unit 14 comprises a member 15 having a high resistance to an electric current, said member in the form shown herein, comprising a cylindrical post or bar made of carbon, preferably graphite. Received over one end portion 15^a of said bar 15 is a cylindrical, metallic cap member 16 tightly fitted thereon. The end wall 16^a of said cap is 50 slightly spaced from the outer end surface

15^b of said bar, and extending thru a central aperture 17 of said wall is the end portion 18 of the stranded wire 11. Said wire end 18 is suitably soldered to said end wall for permanently connecting the lead 10 to the high 55 resistance bar 15. Received over the opposite end 19 of said bar 15, is a metallic member 20 having a socketed portion 21 for snugly receiving said end portion 19. Said member 20 is provided with a flanged head 22 and a 60 flat bifurcated blade member or terminal connector 23 extending therefrom which serves as a terminal member for connecting the lead 10 and unit 14 to any suitable binding post or terminal (not shown). The end portion 65 19 of the graphite bar 15 may be fused with the socket 21 or may simply have a snug sliding fit therein.

For firmly anchoring the member 20 to the bar 15 and for protecting the latter, the socketed portion 21 may be provided with an external thread 25 and a protective tubular casing or sleeve 26 is provided of moldable, insulating material such as porcelain, vulcanized rubber, phenol-condensate products, or the like, said casing 26 having an internally threaded end portion 27 adapted to receive and coat with threads 25 of member 20. The internal diameter of the casing 26 is sufficient to permit it to be slid over the bar 15 and the cap 16 for the threading operation. The end portion 28 of the casing 26 remote from the member 20 and through which the wire conductor 10 slidably extends is reduced in diameter to provide a shoulder 29 adapted to substantially abut the outer peripheral portion of the cap wall 16^a when said tube is screwed to the end member 20, to press and bind the parts in good electric contact. 80

The manner of assembling the unit 14 will 85 now be apparent. The casing 26 is first fitted on the conductor 10. The end portion 18 of the wire 11 is then connected to the cap 16, the latter being then fitted on the resistance bar 15. The terminal member 20 may then be 90 fitted on the outer end 19 of said bar 15, and the casing then pushed to the left, looking at Fig. 1 of the drawing, and screwed to the threaded portion 21 of the terminal member 20. The resistance bar 15 is thus firmly re- 100

tained within the casing 26, good electrical contact assured, and displacement of the terminal member 20 prevented, by the abutting contact between the shoulder 29 and the cap 16. In the assembled position the tubular casing acts as an insulator and also as a handle for the unit when connecting or disconnecting the same to a binding post or terminal.

Obviously, the high resistance element may 10 take the form of a thin coiled wire or any other suitable form.

It will thus be seen that there is provided a device in which the several objects of this invention are achieved, and which is well 15 adapted to meet the conditions of practical use.

As various possible embodiments might be made of the above invention, and as various changes might be made in the embodiment 20 set forth, it is to be understood that all matter herein set forth or shown in the accompanying drawing is to be interpreted as illustrative and not in a limiting sense.

Having thus described my invention I 25 claim as new and desire to secure by Letters Patent:

1. A resistance unit and terminal for attachment to an electrical wire conductor, comprising a terminal connector, a resistance element having one end in electrical contact with 30 said terminal connector, and a tubular casing for the resistance element having at one end an opening through which a wire conductor may extend for connection to the other end 35 of said resistance element, the other end of said casing being detachably connected to said terminal connector, said tubular casing having an inner shoulder coaxing with the resistance element when the parts are in assembled 40 relation.

2. A resistance unit and terminal for attachment to an electrical wire conductor, comprising a terminal connector having a socketed portion, a resistance element having one 45 end fitted in said socketed portion, a cap fitted on the other end of said resistance element and adapted to electrically connect the latter to a wire conductor, and a tubular casing for the resistance element having at one end an 50 opening adapting it for slidable movement over said wire conductor, said end of said casing having an inner shoulder coaxing with the capped end of the resistance element for holding the parts in tight electrical contact, 55 when in assembled relation, and means at the other end of said casing for detachable connection with said electrical connector.

3. A resistance unit and terminal for attachment to an electrical wire conductor, comprising a terminal connector having a socketed portion externally threaded, an elongated resistance element fitted into said socketed portion, a metal cap fitted on the other end of 60 said resistance element and having an opening therein through which the end of a wire

conductor may extend to lie between the cap and said resistance element, a tubular casing for said resistance element having one end reduced, and through which the wire conductor may slidably extend, said reduced portion forming a shoulder against which the cap end of the resistance element may abut, the other end of said tubular casing being threaded to coact with the threads of said terminal connector for detachably securing the parts 70 together and holding them in tight electrical contact.

In testimony whereof I affix my signature.
WILLIAM M. HEINA.
